(57) **CLAIM**

I claim the ornamental design for a menstrual cup, as shown and described.

DESCRIPTION

FIG. 1 is a perspective view of a menstrual cup showing my new design;

FIG. 2 is a front elevation view thereof;

FIG. 3 is a back elevation thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a cross-section view thereof, taken along line (8-8) of FIG. 6, showing the menstrual cup.

The bold broken lines in FIGS. 1, 6, and 8 depict perforations through a layer of material and form part of the claimed design.

The light-weight broken lines are included for the purpose of illustrating environmental structure and form no part of the claimed design.
